UNITED STATES PATENT OFFICE.

JACK J. FELSENFELD, OF BROOKLYN, NEW YORK.

CLASP FOR WRIST-WATCH BRACELETS AND THE LIKE.

Application filed March 13, 1926. Serial No. 94,545.

This invention relates to clasps of the type adapted to secure a bracelet about the wrist of the wearer or necklace about the neck of the wearer. In fact, it relates generally to a clasp adapted to join the severed ends of any band or part, the ends of which are to be secured together under conditions of tension.

The object of the invention is to provide for the clasping of two joining ends of any tension member in such a way that two parts of the clasp may be brought together in a position of minimum tension of the parts to be joined and by a simple relative movement transverse to the line of tension be caused to increase the tension or draw the said parts together a substantial amount and at the same time lock the clasp in closed or clasping position.

To this end, in carrying out my invention, I propose the employment of two parts, a body part and a take-up part each adapted to be secured to the terminal end of a tension member and with the take-up part having a nose first to be engaged with the body part on the side edge thereof and under conditions of minimum tension, and I provide means whereby a simple relative transverse movement between said parts in the nature of a cam and cam-follower tightens the parts to be clasped, effects the closing of the clasp and the locking of the same in closed position.

The above together with further objects and details of my invention will better be understood by reference to the embodiments of my invention to which my claim is directed, solely for purposes of illustration, and which embodiments are described in the following specification in connection with the accompanying drawings which form a part hereof.

In the drawings:

Fig. 1 is a front plan elevation of the two parts of my clasp with parts broken away partly in section and with the parts thereof shown first in starting engagement and in dot and dash lines in locked engagement;

Fig. 2 is an end or edge view of my clasp partly in section; and

Fig. 3 is a similar view of a modification.

My clasp preferably comprises two parts, a body part A and a take-up part B, each part being provided with suitable means such as the eyes 1 and 2 for securing the tension members such as the strings of beads

as may go to make up a wrist-watch bracelet or a necklace or any similar construction. It should be understood, however, that I contemplate any suitable means for the attachment of the tension apparatus.

The body part A may be formed of an ornamental metal shell having a back plate 3 and a front plate 4 boxed in by the edge wall 5 and the edge wall 6. The other two walls 7 and 8, however, function otherwise than as mere boxing walls. The wall 7 is preferably merely an inturned lip extending from the front wall 4 towards the back wall 3 to form a cam-follower and retaining wall 70 but leaving the free entrance slot 9.

In its important function the edge wall 8 provides merely the locking lip 10, although in Fig. 2 it is shown extending over towards the rear wall 3 except for an entranceway, or slot 11 corresponding in size with the slot 9. The slot 11 is unlatched at the bottom to form the notch 12 of a size to pass the camway 13. However, in Fig. 3, this end or edge wall 8 is limited to the locking lip 10 so that the entire edge opening 11' is available for the entrance of the nose 15 of the camway 13. For some purposes, this may be preferable to prevent fumbling in the closing of the clasp.

The take-up part B in addition to the nose 15 comprises in its camway the permanent stress resisting member 16 which together with the interconnecting part 13 complete the camway. Extending out beyond is the web 17 which is of a thickness and in such location as to pass freely through the slot 9. Extending out from the nose 15 is a resilient arm 18 of cross-section similar to the web 17. This arm is provided with a locking notch 20 into which the lip 10 takes to lock the part B to the part A. Fingernail engageable ears 21 and 22 are provided as a ready means of springing the resilient arm 18 to release the parts. Overbending of the arm 18 is prevented positively by means of a post 23 extending up from the web 17 towards the elbow of arm 24, so that its end 25 serves as a stop to limit the releasing movement of arm 18.

In its operation the operation of my clasp is ready, despite the fact that bracelets necessitate for their application a one-handed operation by the intending wearer, my clasp is responsive primarily on account of the fact that the initial engagement between the parts A and B may be effected when the

parts of the clasp are in an out position occasioning little or no tension in the bracelet or similar construction. For example, in Fig. 1, the nose 15 is thrust into the body part A over the lip 7. It is guided in the desired transverse direction between the back wall 3 and the front wall 4, and in one embodiment by the notch 12, although the tension of the bracelet may render the provision of this notch 12 unnecessary. A finger pressure upon edge wall 6 and the outer edges of the ears 21 and 22 is sufficient to effect a transverse closing movement of the two parts of my clasp so that the camway 15, 13, and 16 rides up on the lip 7 drawing the fastening devices 1 and 2 closer to each other, tightening the bracelet, and at the same time closing the clasp into the position shown in dot and dash lines for part B in Fig. 1. In this position, the locking lip engages in the notch 20 with a snap action locking the parts together against accidental disengagement although the stress from the tension of the bracelet is resisted by the part 16 riding on the lip 7 and little or no stress is applied between the notch and the lip 20 and 10, although this notch and lip are effective in preventing any rocking of the two main parts A and B in their engaged position.

30 The inventive thought may have a variety of expressions as is contemplated in what I claim and desire to secure by United States Letters Patent as follows:

1. A self-tightening clasp for bracelets and the like comprising a body part and a take-up part respectively adapted to be secured to the tension ends of a bracelet or the like; means on said body part permitting transverse entrance thereinto by said take-up part and preventing relative movement between said parts at right-angles to said transverse movement; and cooperating relatively slidable cam and cam-follower means respectively associated with said parts said cam means having an incline whereby said transverse movement between said parts automatically effects a take-up movement of a substantial amount between said parts in the plane of said transverse movement and at right-angles to said transverse movement.

2. A self-tightening clasp comprising a body part and a take-up part respectively adapted to be secured to the severed tension ends of a member to be clasped and tightened; terminal connectors respectively on said body part and said take-up part to be secured to the ends of said member; means formed respectively on said body part and said take-up part for engaging said parts together in relatively open position and cooperating inclined cam and cam follower means formed on said parts responsive to a transverse pressure upon the engaged two parts of said clasp to effect a two-directional movement between said parts relatively to

each other, one direction of said movement being a transverse movement into registration, and the other movement being at right-angles to said transverse movement to effect an approach towards one another of said terminal connectors whereby a take-up or tightening functioning is had.

3. A clasp for bracelets and the like comprising a body part and a take-up part; said body part comprising a flat sheet metal box with an opening at one end; terminal connector means along one edge of said box; the other edge of said box being formed by a lip leaving a slot between the edge of said lip and the edge of said box; said take-up part having a nose adapted to enter the opening of said body part and engage said lip in relatively open position for the parts of said clasp; said take-up part having terminal connector means spaced apart from said nose; and an inclined camway extending from said nose laterally and out towards said terminal connector means and adapted to impart an approach between said terminal connector means in response to a relative transverse force imparted to said body part and said take-up part respectively, and whereby said force effects between said parts a relative transverse approach into registration, and in addition a relative approach at right-angles to said transverse approach.

4. The structure as defined in claim 3 and further characterized by the fact that a releasable latch is provided to hold the body part and the take up part in closed relation.

5. A bracelet clasp comprising a thin hollow box-like body part having a terminal edge wall provided with bracelet attaching means, a front and a back joined by said terminal edge wall, means to prevent the spreading out of the edges of said front and back opposite said terminal edge wall and a lip inturned from one of said edges of said front and back opposite said terminal edge wall, said lip forming a transverse slideway and leaving a slot between said edges along the edge of said inturned lip; and a take-up part to be seated in said body part having an elongated thickened member to ride on said inturned lip into said body-part and of a cross-section too great to pass through said slot, a terminal web extending out from said thickened member and having terminal means for attaching it to a bracelet and of a thinness to pass out through said slot.

6. A bracelet clasp comprising a thin, hollow box-like body part having a terminal edge wall provided with bracelet attaching means, a front and a back joined by said terminal edge wall, means to prevent the spreading out of the edges of said front and back opposite said terminal edge wall and a lip inturned from one of said edges of said front and back opposite said terminal edge wall, said lip forming a transverse slideway

and leaving a slot between said edges along the edge of said inturned lip; and a take-up part to be seated in said body part, having an elongated thickened member to ride on said inturned lip into said body-part and of a cross section too great to pass through said slot, a terminal web extending out from said thickened member and having terminal means for attaching it to a bracelet and of a thinness to pass out through said slot, a resilient arm spaced from said thickened member, means for attaching one end of said arm to said thickened member, latching detent means mutually provided on the free end of said resilient arm and said terminal 15 edge wall for locking said parts together, finger engageable means provided on the free end of said resilient arm and the adjacent end of said thickened member for operating said arm and engaging said parts, 20 and a stop post means cooperating between the free end of said resilient arm and the adjacent end of said thickened member to limit the bending of said resilient arm.

In witness whereof, I have signed my 25 name to this specification this 12th day of March, 1926.

JACK J. FELSENFELD.
